INVENTOR.

UNITED STATES PATENT OFFICE.

BRUCE H. REDDITT, OF BALTIMORE, MARYLAND.

TYPE-WRITER.

1,264,557.

Specification of Letters Patent. Patented Apr. 30, 1918.

Application filed October 30, 1917. Serial No. 199,304.

To all whom it may concern:

Be it known that I, BRUCE H. REDDITT, a citizen of the United States, residing at Baltimore, in the city of Baltimore and State of Maryland, have invented a new and useful Attachment for an Improvement in Type-Writers, of which the following is a specification.

My invention relates to typewriter paper indicators and page-end indicators and stops, wherein a steel cylinder, built or placed on the shaft of the platen, having cut in its convex surface a spiral groove, operates a collar or engaging projection from a sliding or rolling indicator or stop, so as to move the indicator stop along a track and scale as the platen is turned and the paper advanced, this indicator-stop serving two purposes, namely: first, to show constantly on the two scales the distance or number of line spaces through which the paper has been moved, as well as the distance or number of line spaces yet remaining to be written upon; and, second, to automatically lock the platen against being turned farther when it has already been turned through a certain distance, or through a given number of line spaces, which distance or number of line spaces is arbitrarily fixed in advance by the operator and the stop set accordingly.

I attain these objects by the mechanism illustrated in the accompanying drawing, which is an oblique view of the front, right-hand side or corner of the machine, in which drawing—

A is a steel cylinder, made as an integral part of, or firmly attached to the shaft of the platen, and has cut in its lateral surface a spiral groove, N, rectangular in cross-section. B is an engaging projection, or collar, attached to the stop C by the hinge R, and having on the lower side at this hinge a projection P, which engages a seat in the spring F, this spring serving to hold the projection B in its place of engagement in the groove on cylinder A. The spring is attached at its elastic end to the bottom of the stop C. The stop C slides or rolls along the track or plate D, and may either slide or operate on anti-friction rollers as shown in the drawing, so that it is free to move from left to right, or vice versa, as the collar B moves along the cylinder A. G is an upward extension of the rear wall of the box or frame J—K, and has in its front lateral surface a rectangular depression L, in which fits the sliding scale H,

permanently attached to the stop E. The surface of G also is provided with a scale, as indicated, which is the reverse of the scale of the slide H. The movable stop E is held rigidly at any desired point by means of the set-screw S. Both scales referred to above are shown in the drawing as representing the distance in line spaces through which the platen and therefore the paper, has been moved or rotated, and through which they are yet to be rotated before the stop comes into action, respectively.

Before feeding or rolling a sheet of paper into the machine, the projection, or collar, B is raised by the knob on the upper surface thereof and moved to the right until it strikes and stops at the frame plate K, the collar B being then lowered against the cylinder A. If the collar does not immediately fit into the groove, the platen is turned backward until this takes place, at which point the platen stops. The stop E is then, by means of the set-screw S, made stationary at a point on the scale of G at which the operator wishes to stop the writing, or at which is the desired bottom marginal point on the paper, this reading on the scale depending upon the size of the paper used and the amount of margin desired at the bottom of the sheet. The scale G may have noted at the proper points the points for standard papers according to their lengths, such as "legal", "letter", "note", etc., which standard sizes of paper may be immediately determined on sight, and therefore it would not be necessary to know even the lengths of the papers in lines or inches, etc., before setting the stop E.

The paper is then fed or rolled into the machine in the usual way, and the writing done exactly as if the mechanism herein described were not in place. As the paper is rolled in, the cylinder A turns so that the spiral groove N moves, on the principle of the simple screw, the collar B along its track. When the paper has been turned through the distance for which the stop E has been set, the moving stop C strikes the stationary stop E, thus locking the platen and preventing its being turned further.

If it be desired to continue further on the same sheet, it is necessary only to lift the collar B to an upright position, thus entirely disengaging the mechanism. Likewise, when there is no need at all for the indicator-stop, as in filling in blanks, and

such work, it may be disengaged in the same way, and the machine used as if it were not there.

I claim:

- 5 1. In a paper indicator and page-end stop, in combination, an actuating member consisting of a worm-threaded cylinder driven by the platen shaft, a moving pointer, a follower on the pointer controlled by said actuating member to move the pointer proportionately to the platen roll, a fixed stop to be engaged by the pointer at the end of its traverse to check the platen at a predetermined point on the page, and a 45 plurality of scales to be traversed by the pointer, one being stationary and graduated in correspondence with the line spacing of the machine, and the other being manually adjustable together with the fixed stop and graduated in inverse correspondence with the normal line spacing of the machine and the direction of motion of the pointer during the operation of the machine, substantially as set forth. 55
- 10 2. In a paper indicator and page-end stop, in combination, an actuating member consisting of a worm-threaded cylinder driven by the platen shaft, a moving pointer, a follower on the pointer controlled by said actuating member to move the pointer proportionately to the platen roll, a fixed stop to be engaged by the pointer at the end of its traverse to check the platen at a predetermined point on the page, and a scale to be traversed by the pointer, the same being graduated in correspondence with the line spacing of the machine, substantially as set forth. 60
- 15 3. In a paper indicator and page-end stop, in combination, an actuating member consisting of a worm-threaded cylinder driven by the platen shaft, a moving pointer, a follower on the pointer controlled by said actuating member to move the pointer proportionately to the platen roll, a fixed stop to be engaged by the pointer at the end of its traverse to check the platen at a predetermined point on the page, a scale to be traversed by the pointer, the same being permanently attached to the fixed stop, and graduated in inverse correspondence with the normal line spacing of the machine and in the direction of the motion of the pointer during the operation of the machine, substantially as set forth. 65
- 20 4. In a paper indicator and page-end stop, in combination, an actuating member consisting of a worm-threaded cylinder driven by the platen shaft, a moving pointer, a follower on the pointer controlled by said actuating member to move the pointer proportionately to the platen roll, a spring-hinge whereby the follower is attached to the moving pointer, thus to enable the operator to disengage the indicating and stopping mechanism at will, a fixed stop to be engaged by the pointer at the end of its traverse to check the platen at a predetermined point on the page, and a plurality of scales to be traversed by the pointer, one being stationary and graduated in correspondence with the line spacing of the machine, and the other being manually adjustable together with the fixed stop, and graduated in inverse correspondence with the normal line spacing of the machine and direction of motion of the pointer during the operation of the machine, substantially as set forth in the drawing and specification forming a part of this application. 70
